KNIFE CLEANER FOR ROTARY TOBACCO-LEAF CUTTING MACHINES

Henry William Langrish, Deptford, London, England, assignor to Molins Machine Company, Limited, Deptford, London, England

Application October 2, 1941, Serial No. 413,354
In Great Britain October 7, 1940

2 Claims.

(Cl. 146—106)

This invention concerns improvements in or relating to the removal of material from a rotating element such, for example, as from a knife or a knife holder of a rotary tobacco leaf cutting machine.

The present invention is especially useful in connection with a rotary tobacco leaf cutting machine in which machine there is, during the operation of the machine, a tendency for gummy or resinous substances to adhere to the knife or knives and in some cases even to the knife holder or holders. If these substances are not removed in good time they build up until a rubber-like strip is formed and there is then a possibility that the strip will become dislodged and will fall unnoticed into the product of the machine. It is, of course, most undesirable that such strips should become included in the product of the machine and over a period of years many suggestions have been made for cleaning or scraping the knife during the operation of the machine. A number of such suggestions have been put into practice, but none has been fully satisfactory, either because the operation has not been efficient or because the suggested device has been difficult or costly to construct and to operate.

A further problem which can be overcome by the use of the present invention is that of burrs which appear on the back of the knife consequent upon metal from the knife edge being turned over due to the frequent grinding of the knife during operation of the machine. Heretofore, there has been the possibility of such burrs becoming broken off and falling into the tobacco. By the present invention, however, it is possible to remove the burrs as they are formed.

According to the present invention there is provided in a machine, a rotatable element and a remover element (e. g. a scraper or abrasive) adapted to move in an arcuate path to remove material from the rotatable element (e. g. by grinding or scraping substantially in the direction of a line on the rotatable element inclined to the direction of rotation thereof and in a plane normal to the axis of rotation of the rotatable element, the movement of the remover element being substantially along and at the speed at which a trace in space is formed by a point progressing outwardly along the said line at successive moments during movement of the rotatable element).

Further according to the invention there is provided in a machine, a rotatable element and a remover element (e. g. a scraper or abrasive)

adapted to move in an arcuate path to remove material from the rotatable element (e. g. by grinding or scraping respectively) substantially in the direction of a straight or substantially straight line on the rotatable element, inclined to the direction of rotation thereof and in a plane normal to the axis of rotation of the rotatable element, the movement of the remover element being substantially along and at the speed at which a trace in space is formed by a point progressing outwardly along the said line at successive moments during the movement of the rotatable element.

The remover element may be yieldingly mounted (e. g. articulated) and adapted to be urged to engage the co-operating part of the rotatable element (e. g. by a spring or by centrifugal force).

The invention will be more particularly described by way of example with reference to the accompanying drawings in which:—

Figure 1 is a front elevation of a portion of a rotary tobacco cutting machine showing a knife carrier and a remover element constructed according to the invention.

Figure 2 is a diagram showing a method of determining the size and location of the remover element.

Figure 3 is a front elevation and Figure 4 is a side elevation of a scraper.

Figure 5 is a front elevation and Figure 6 is a side elevation of another form of scraper.

Figure 7 is a front elevation and Figure 8 a side elevation of another form of scraper.

Figures 9, 10 and 11 are diagrams illustrating the action of different forms of scrapers.

Fig. 12 is a view of a portion of a modified form of scraper.

Referring to Figure 1, the knife carrier 1 is carried on a shaft 2 rotatably mounted in a frame 3 of the tobacco cutting machine and in the form of machine illustrated, five knives 4 are illustrated and disposed at regular intervals around the knife carrier 1. The tobacco "cheese" which is to be cut issues from a mouthpiece 5 and the knives 4 move forwardly over the mouthpiece and contact therewith in order to effect the cutting operation.

In order to grind the edges of the knives 4 a grinder 6 is provided automatically to grind the knives during operation of the machine and the knives pass over the surface of the grinder and are sharpened thereby before they operate to cut the "cheese" of tobacco fed through the

mouthpiece 5. It will be seen from the figure that the cutting edge of the knife is inclined at an angle with respect to a radial line drawn from the centre of rotation. The extent of this angle is chosen by experiment to find the best for cutting a "cheese" of the cross-section determined by the particular mouthpiece. The edge of each knife lies in a plane normal to the axis of rotation of the knife carrier. The edge of each knife may thus be said to be a line on the rotatable head.

At some suitable position to be determined by the method hereinafter described with respect to Figure 2, a second shaft 10 is mounted for rotation, the axis of this second shaft being parallel with that of the knife carrier shaft 2. Secured to the shaft 10 for arcuate movement therewith (e. g. rotation) is a remover element which comprises a scraper 7. The scraper is fixed to a block 11 which is pivoted at 8 to a lever 9 fixed on the shaft 10 which forms the axis of rotation of the remover element. The block 11 is capable of slight movement about the pin 8 against the tension of the spring 12. The lever 9 may be rotated in any convenient manner but for simplicity it is shown as being driven by a chain from the shaft 2 of the knife carrier. To this shaft there is fixed a sprocket wheel 13 on which a chain 14 runs; the chain also passes over a small sprocket 15 fixed to the spindle 10 about the axis of which the element revolves. The operative portion of the scraper is, in one form, of substantially inverted V shape and at the apex of the V the scraper is arranged to engage the knife edge while on one side of the V it engages the back of the knife and on the other side of the V engages the chamfer on the front of the knife, all in the manner to be described hereafter with reference to Figures 3 and 4.

The orbital path of the knife edge is intersected by the path of the apex of the V and the relative speeds of the knife and the scraper and the distance of each from the axis about which it moves are so chosen that the trace of the extreme point of the apex of the V coincides with the straight edge of the knife. If, however, another point on the scraper is selected for consideration, for example a point on that side of the V which engages the back of the knife, the trace of this point if projected on to the knife, is a straight line which is parallel with the edge of the knife although the point will lie in a plane behind that of the knife edge.

A method of laying out the construction in accordance with the invention is shown in Figure 2. The distance through which it is desired that the knife shall be moved during the scraping operation is first selected and as shown on the diagram, this distance corresponds to the distance between the ends *a* and *m* of the radial lines *R*1 and *R*2. The orbital path of the knife is, of course, known and as shown the corners of the knife travel along arcs struck about the axis of rotation from the points *A* and *G*. The angular speed at which the knife is moved is also known and is constant. A number of equispaced points *g* to *a* respectively representing selected positions of a point progressing outwardly along the edge are next selected along the knife edge and through these points are drawn arcuate lines *A* to *G* struck about the axis of rotation *G* of the knife carrier. These lines pass through that part of the orbital path within which scraping is to be effected. A number of lines, *a*, *h*, *i*, *j*, *k*, *l*, *m*, equal to the number of

equispaced points *a* to *g* and themselves equally spaced to divide the selected part of the orbital path and representing the positions of the knife edge at selected moments during rotation of a knife, are then drawn so as to intersect the arcuate lines *A* to *G*. As will be seen from the figure, the knife edge lies at an angle of 32° with respect to the radius *R*1 so that the upper position of the knife edge is easily drawn in by placing it at an angle of 32° with respect to the radius *R*2. A line *X*—*Y* drawn through the intersections *g*, *n*, *o*, *p*, *q*, *r*, *m* so obtained is an arc of a circle, the radius *Z* of which can be readily ascertained by construction and measurement, thus determining the position for the axis 10 of rotation of the scraper. This arc *g*, *n*, *o*, *p*, *q*, *r*, *m*, is therefore a trace in space formed by a point progressing outwardly along the line *a*, *g* at successive moments during movement of the rotatable knife carrier. This arc having been obtained, the relative angular speeds of the knife and scraper can be readily calculated once the angular speed of the knife is known, since the linear speed of the scraper must equal the speed at which the trace is formed.

In the machine being described the scraper makes five revolutions to two of the knife carrier so that each knife is scraped during each second revolution of the knife carrier.

As above described the arrangement is adapted to scrape the entire straight edge of a knife. Since, however, the knife is continually ground during the operation of the machine by the grinding wheel shown in Figure 1, the edge of the knife is usually not quite straight but is concave. The extent to which the edge is not straight is about .005" to .01" between the opposite corners of the edge. In some cases it is not important that the whole of the edge shall be engaged by the scraper, and in these cases moving the scraper over the edge and in close proximity thereto will ensure that no undue accumulation of resinous substances will occur on the knife. When, however, it is desired to scrape the entire edge in such cases, the scraper is resiliently mounted on the lever secured to the scraper shaft as described with reference to Figure 1. The scraper could of course be articulated and arranged to move out by centrifugal force against the knife edge to follow the latter where it deviates from a straight line.

Similarly if it is not convenient to position the axis of rotation of the scraper in its exact position so as to ensure that it moves along the trace *g*, *n*, *o*, *p*, *q*, *r*, *m*, then the scraper may be resiliently mounted or arranged to move out as above mentioned by centrifugal force.

It should also be appreciated that when it is not necessary that the scraper shall engage the knife at all positions the axis of rotation of the scraper need not be so accurately located as to ensure that the scraper follows the said trace. In such a case, however, it will be understood that the direction of movement of the scraper would, nevertheless, require to be substantially straight in order to obtain the requisite scraping effect.

By frequently engaging the edge of the knife with the scraper in the manner above described, any burrs which tend to form are quickly removed.

Referring to Figures 3-11 which show various forms of scrapers and the manner in which they operate to remove material from the rotatable element, the scraper shown in Figures 3 and 4

is of substantially inverted V shape, the apex 15 of the V being arranged to engage the knife edge as shown in Figure 9 while the side 17 of the V engages the back of the knife and part of the clamp while the other side 18 of the V engages a chamfer on the front of the knife. In Figures 5 and 6 the scraper is only provided with one scraping edge 19 which engages the clamp on the back of the knife as shown in Figure 10. The scraper shown in Figures 7 and 8 is adapted to remove material from the ground face of the knife and the neighbouring face of the front portion of the knife, i. e. the face nearer to the "cheese" of tobacco and part of the front clamp. This scraper operates in the manner shown in Figure 11. If desired other shapes of scrapers may be designed to scrape, for example the whole of the knife and parts of the front and back clamps. This is shown in Fig. 12 where two scrapers are mounted on the block 11, one behind the other, each scraper dealing with a part of the surface on which the resinous material accumulates, the leading scraper 7a being that shown in Figures 3, 4, and 9, and the following scraper 7b being that shown in Figures 7, 8, and 11.

Although in the examples given, the edge of the knife has been considered as straight or substantially straight and the edge has been assumed to be regular, the invention could also be applied to constructions in which the edge whether irregular or regular has parts which deviate from a straight or substantially straight line to a small extent. For instance, if in a particular application it sufficed for the remover element to be at a certain maximum distance, it would clearly be possible to construct an edge in which there was either irregularity or curvature to that extent and the words "substantially in the direction of a line" and "substantially along a trace" when used herein and in the claims mean that the remover element (whether yieldably mounted on a carrier or not) passes along the line or trace at all times within the minimum distance necessary for performing the intended function. Where, however, the remover element is to act as a grinder or hone, it is clear that the edge of the knife must be a very close approximation to a straight line unless the remover element is yieldably mounted to allow it to compensate for any departure of the knife edge from a straight line. It is to be appreciated, however,

that any such departure from the straight line will be limited by consideration of expediency.

What I claim as my invention and desire to secure by Letters Patent is:

- 5 1. In a tobacco cutting machine, a rotatable knife having a substantially straight cutting edge inclined to the radial in a direction outwardly and rearwardly with respect to the direction of rotation and in a plane normal to the axis of rotation, and a scraper blade driven in timed relationship with the knife and shaped to engage the cutting edge and areas in proximity to the cutting edge of the knife to remove material therefrom, during movement of the knife, and
10 means supporting said blade for movement in a curved path about an axis parallel to and spaced from the knife axis in the same angular direction as the knife and outwardly across the path of the knife in a zone laterally removed from a line connecting the axes of the knife and blade, means driving said knife and blade in such timed relation that during the movement of the blade along the knife, the blade is caused to sweep lengthwise of the whole of said cutting edge with
15 a point on said blade progressively engaged with successive points on said cutting edge, said supporting means retaining said blade against axial displacement during such outward movement.
2. In a tobacco cutting machine, a rotatable
20 knife having a substantially straight cutting edge inclined to the radial in a direction outwardly and rearwardly with respect to the direction of rotation and in a plane normal to the axis of rotation, and a scraper blade driven in timed relationship with the knife and shaped to engage the cutting edge and areas in proximity to the cutting edge of the knife to remove material therefrom, during movement of the knife, and
25 means supporting said knife and blade for rotation on spaced parallel axes and in the same direction, whereby the remover element may move outwardly across the path of the knife in a zone laterally removed from a line connecting the axes of the knife and blade, means yieldingly
30 supporting said blade on said last named means, means driving said knife and blade in such timed relation that during the movement of the blade along the knife, the blade is caused to sweep lengthwise of the whole of said cutting edge with
35 a point on said blade progressively engaged with successive points on said cutting edge.
3. In a tobacco cutting machine, a rotatable
40 knife having a substantially straight cutting edge inclined to the radial in a direction outwardly and rearwardly with respect to the direction of rotation and in a plane normal to the axis of rotation, and a scraper blade driven in timed relationship with the knife and shaped to engage the cutting edge and areas in proximity to the cutting edge of the knife to remove material therefrom, during movement of the knife, and
45 means supporting said knife and blade for rotation on spaced parallel axes and in the same direction, whereby the remover element may move outwardly across the path of the knife in a zone laterally removed from a line connecting the axes of the knife and blade, means yieldingly
50 supporting said blade on said last named means, means driving said knife and blade in such timed relation that during the movement of the blade along the knife, the blade is caused to sweep lengthwise of the whole of said cutting edge with
a point on said blade progressively engaged with successive points on said cutting edge.

HENRY WILLIAM LANGRISH.
